CAN PIERCER

Harry W. Halvorsen, 15646 Eastwood, Detroit 5, Mich.
Filed Mar. 6, 1961, Ser. No. 93,642
2 Claims. (Cl. 30—16)

This invention relates to container openers and, in particular, to can piercers.

One object of this invention is to provide a can piercer which is so constructed as to enable a triangular hole to be quickly and easily punched in one end of the can, for pouring liquid contents therefrom.

Another object is to provide a can piercer of the foregoing character which is so constructed and arranged as to be operated by the pressure of the palm of the hand, thereby applying a strong force to cause the prong to enter the can top.

Another object is to provide a can piercer of the foregoing character wherein the area of the can opener adjacent the prong has a bead or rib surrounding the prong opening so as to reinforce and enhance the rigidity of the can piercer.

Another object is to provide a can piercer of the foregoing character wherein an arcuate flange substantially perpendicular to the palm rest of the can piercer is provided adjacent the tip of the prong, which is inclined downwardly toward the flange, so as not only to strengthen the can piercer but also to provide a locating stop for the accurate positioning of the can top opening and additionally to shield the point of the prong from pricking the fingers or hand of the operator.

Other objects and advantages of the invention will become apparent during the course of the following description of the accompanying drawing, wherein:

FIGURE 1 is a top plan view of a can piercer according to one form of the invention shown as applied to the top of a can;

FIGURE 2 is a vertical section taken along the line 2—2 in FIGURE 1, with the position of the can indicated in dotted lines; and

FIGURE 3 is a left-hand end elevation of the can piercer shown in FIGURE 1.

This is a continuation-in-part with reference to FIGURES 6 and 7 of my co-pending application Serial No. 821,230, filed June 19, 1959, for "Palm-Operated Can Opener," which was issued May 16, 1961, as U.S. Patent 2,984,002.

Referring to the drawing in detail, FIGURES 1 and 2 show a can piercer, generally designated 10, according to one form of the invention as applied to the top T of a can C and consisting generally of a palm rest 12, a piercing prong 14, and an arcuate stop flange 16. The can C is of any conventional type, usually cylindrical, with a flat top T joined to cylindrical side wall S in an annular line, with or without a slight bead.

The palm rest 12 of the can piercer 10 is of roughly sector-shaped form with its widest end 18 joining the upper edge of the flange 16 in a rounded arcuate junction 20 (FIGURE 2). The palm rest 12 has arcuate side edges 22 converging toward the rear edge 24 which is conveniently straight. The palm rest 12 is generally flat, with a hole 26 near its rearward edge 24 for hanging the can piercer 10 upon a hook (not shown).

The part of the palm rest 12 adjacent its front edge 18 is provided with a raised or upwardly-dished portion 28 (FIGURES 1 and 2) from which the piercing prong 14 is inclined downwardly from a V-shaped opening 30, the prong 14 having a sharp point 32. The V-shaped opening remains after the prong is struck downward by

2

a die from the raised portion 28. The prong 14 near its junction with the raised portion 28 is raised as at 34, which increases the strength and rigidity of the prong. The raised portion 34 of the prong 14 and the raised portion 28 of which it is a part have a beaded or curved junction 36 with the remainder or flat portion 38 of the palm rest 12.

The arcuate stop flange 16 has downwardly-converging side or end edges 40 and a substantially flat bottom edge 42 with a central inverted U-shaped opening or notch 44 in line with the point 32 of the prong 14. This construction enables the prong 14 to be quickly and easily cleaned by placing it under a water faucet with the stream of water passing through the notch 44.

In the operation of the can piercer 10, of the invention, the user places the can piercer 10 lightly upon the top T of the can C and with his fingers pushes the flange 16 against the adjacent side S of the can C. This positions the can piercer in the proper location for piercing, since the arcuate flange 16 roughly fits the annular curvature of the rim R of the can C. He then applies downward pressure by means of his palm upon the palm rest 12 with such force as to cause the point 32 of the prong 14 to pierce the top T of the can C, leaving a triangular opening O therein, and a triangular flap F extending downwardly and forwardly toward the rim R, the flap F being formed and pressed down into its inclined position by the inclined prong 14.

The user then lifts the can piercer 10 by placing his fingers either under the lower edge of the flange 16 or under the rearward edge 24 of the palm rest 12. If smooth and even pouring is desired, a second opening is made diametrically opposite the first opening O in order to let in the air as the liquid flows out the other opening O.

What I claim is:

1. A can piercer comprising a generally-flat approximately sector-shaped palm rest having an arcuate forward end of extended width adapted to radially overlie the top of the can to be pierced, an arcuate stop flange integral with and extending downwardly from said arcuate forward end and extending substantially between the opposite extremities of said forward end, and a pointed piercing prong integral with and extending downwardly toward said stop flange, said palm rest having an approximately triangular opening pointing toward said flange and said piercing prong having a junction edge with said palm rest at the side of said opening remote from said flange.
2. A can piercer, according to claim 1, wherein said palm rest has an approximately W-shaped reinforcing rib raised above the top surface thereof with the side portions of said rib extending along the opposite sides of said opening and with the portion of said rib extending across the base of said prong and downwardly into said prong.
